VACUUM TUBE GRID CONSTRUCTION

Charles J. Kayko and Paul A. Stoll, Jackson,
Mich., assignors to The Sparks-Withington
Company, Jackson, Mich., a corporation of
Ohio

Application April 15, 1931, Serial No. 530,262

1 Claim. (Cl. 250—27.5)

This invention relates to improvements in grid construction of vacuum tubes for radio and other purposes, and particularly to vacuum tubes employing cylindrical electrodes.

5 The grid electrode usually consists of fine wire wound in the form of a helix and having a single supporting rod contacting each turn of the helix. The natural requirement of a vacuum tube employing a grid electrode is that the wire forming 10 the grid be of relatively small diameter so as to offer little resistance to the electron flow between cathode and anode. However, the separate turns of fine wire forming the grid are subjected to 15 mechanical vibration causing plate current modulation or what is commonly known as microphonic action.

It is, therefore, an object of this invention to provide a grid structure for a vacuum tube of comparatively fine wire that will not produce microphonic action.

It is a further object of this invention to produce a grid structure employing only one supporting member, but utilizing additional means for increasing the rigidity of the grid assembly.

20 Other objects and advantages relate to details of the structure, and will be apparent from the following description, taken in connection with the accompanying drawing in which:—

Figure 1 is a perspective view of a vacuum tube 25 electrode assembly embodying our invention.

Figure 2 is an elevation view of a tube having a portion of the envelope broken away to show the electrodes.

Figure 3 is a sectional view taken along line 30 3—3 of Figure 2.

Figure 4 is an elevation view of the grid assembly of our invention.

A conventional heater type vacuum tube 1 is 35 illustrated in Figure 2 having a base 2 and a press 4 for supporting the electrodes. The electrodes are shown to a better advantage in Figure 1. Rising from press 4 are a plurality of rods which 40 serve as supports for the concentrically spaced electrodes as well as electrical connections to the same.

Anode 6 is cylindrical in form and is provided 45 with a flange 7 which may be secured to rod 5. Rod 5 is sealed into press 4 near one end thereof and extends beyond the anode 6. Rod 8 is practically the same length as rod 5 and is positioned 50 near the opposite end of the press as shown.

An insulating member 9 joins rods 5 and 8 at their free ends forming a frame-work for supporting and spacing the remaining electrodes. A 55 rod 10 having its end portion bent parallel to the

top of the press provides a support for the lower end of the heater type cathode 11. The upper end of cathode 11 is supported by rod 12 passing through insulator 9.

The cathode, in this instance, is shown comprising a metallic tube 13 provided with an electron-emitting coating 14. The ends of tube 13 are provided with insulating plugs 15 which support a heater element 16 subtended by rods 12 and 25. Electrical connections to the heater are made through rod 10 which is connected to rod 25 and through a cross rod 17 connecting rod 12 to rod 8. Connection to the cathode is made by means of a metallic strip 18 secured at one end to the electron-emitting surface 14 and at the other end to rod 19 sealed in the press.

Grid electrode 20, in this instance, is concentrically positioned with respect to the cathode 11 and anode 6. The grid assembly as shown in Figure 4, comprises a supporting rod 22 to which are secured 75 the grid wires wound in the form of a helix.

Rod 22 is shown in Figure 1 supported at its lower end by a rod 21 sealed in the press and at its upper end by the insulating member 9. Grid 80 wires 23 are preferably welded at each turn to rod 22. In addition, a rod 24 of much smaller diameter than rod 22 is provided diametrically opposite the latter. The grid wires are also preferably welded at each turn to rod 24 so that the 85 rod is electrically and mechanically connected to each turn of the grid.

In practice, we have found that rod 24 need be only from two to three times the diameter of grid wires 23. This construction produces a rigid 90 assembly that is substantially free from mechanical vibration during normal tube operation. This construction has enabled us to eliminate microphonic action due to plate current modulation set up by vibration of the grid electrode.

It is to be understood that the foregoing disclosure is merely for the purpose of illustration, and that the invention may be broadly applied to different types of grid structures, without departing from the spirit and scope of the appended 100 claim.

We claim:

A vacuum tube structure comprising an evacuated bulb including a press, a plurality of metallic members held in said press two of which extend substantially the full length of said bulb and the remainder terminating a short distance from said press, an insulating member mounted upon the free ends of said long metallic members, a cathode and heater therefor positioned 105 110

between said long metallic members, a heater lead-in conductor secured to one of said short metallic members for supporting one end of said cathode, a second heater lead-in conductor extending through said insulating member and secured to one of said long metallic members for supporting the other end of said cathode, an anode positioned about said cathode and supported by the other of said long metallic members, a grid electrode positioned between said anode and cathode comprising a fine wire helix

secured to a support rod extending beyond the ends thereof and having its lower end secured to another of said short metallic members and its upper end extending through said insulating member, and a second rod of smaller diameter disposed at substantially right angles to the turns of said helix and secured only thereto for preventing microphonic action in the tube.

CHARLES J. KAYKO.
